LOCAL ANAESTHETICALLY ACTIVE PHARMACEUTICAL PREPARATION AND METHOD OF PREPARING THE SAME

Carl Rohmann, Jena, Germany

No Drawing. Application September 18, 1935,
Serial No. 41,025. In Germany July 10, 1934

12 Claims. (Cl. 260—104)

It has already been known for a long time that the water soluble salts of diethylamino-ethenyl p-amino-benzoates are anaesthetically active. The chlorhydrate of the diethylamino-ethenyl p-amino-benzoate is generally known in medicine by the trade name "novocaine" and is used in order to produce local anaesthesia instead of cocaine formerly exclusively applied. By modification of the aminoalcohol esterified with p-amino-benzoic acid and by the introduction of substituents into the amino group of the p-amino-benzoic acid and also by introducing substituents into the benzene nucleus, compounds have been prepared, closely related to novocaine, but more powerful as local anaesthetics than novocaine itself.

By replacing the amino group in p-position by an alkoxy-group the present invention enters a new way. Using such an alkoxy-group that contains 3-6 carbon atoms, products are obtained the water soluble salts of which are considerably more powerful local anaesthetics than novocaine. The new products are as active as the most powerful of the compounds mentioned above, but essentially easier to produce. Furthermore the new preparations are distinguished by the rather unexpected combination of high efficiency and remarkably low toxicity.

The new local anaesthetically active preparations are the water soluble salts of alkoxy-di-alkylene-amino p-alkoxy-benzoates of the general formula:

where R^1 is an alkyl residue with 3-6 carbon atoms, R^2 is an alkylenic residue, preferably with 2 or 3 carbon atoms. R^3 and R^4 are two equal or different alkyl residues of any number of carbon atoms and Ac is an acid radical forming a water soluble salt with the ester of the amino alcohol.

It will be noted that in the compounds identified by the general formula given above, the benzene nucleus has no substituents in the ortho and the meta positions relatively to the carboxyl group, this being indicated by the part C_6H_4 of said formula.

R^1 cannot only be a saturated alkyl residue, such as the propyl-, butyl- or amyl-residue, but also an unsaturated residue, as for example the allyl-group. Furthermore saturated or unsaturated cycloaliphatic residues such as the cyclohexyl-group and the cyclohexenyl-group are to be taken into consideration.

R^2 may be, as already mentioned, preferably the alkylenic residues with 2-3 carbon atoms, i. e. the ethylene- and the propylene-group. But

higher alkylenic residues can take their place as well in certain cases. R^3 and R^4 will be chosen to be equal in most cases, since the dialkyl amines with 2 equal substituents are easier to produce than the dialkylamines with unequal substituents. For R^3 and R^4 the lowest alkyl radicals such as the methyl group as well as the higher alkyl radicals such as the ethyl- and the propyl-group are available. Finally carbon chains possessing two free valencies can take the place of the two alkyl residues, thus for example a piperidyl group replacing the dialkyl amino group when a five membered chain is chosen.

The physiologically mostly indifferent ions such as the chlorine ion are available as the above mentioned acid radical Ac . But organic ions such as the lactic acid ion are appropriate as well, as long as they are able to give a water soluble salt with the amino-alcohol ester.

The production of the new local anaesthetically active preparation is preferably carried out as follows: The phenolic hydroxyl group is etherified according to known methods, for example by means of alkyl halogenides, alkyl sulphonates or dialkyl sulphates. The reaction is carried out in alkaline solution to fix the acid produced. Since the alkyl substituted phenolic hydroxyl has to contain an alkyl residue with 3-6 carbon atoms, the corresponding alkyl halogenides, alkyl sulphonates or dialkyl sulphates only are to be taken into consideration.

The resulting p-alkoxy-benzoic acids are transformed into the corresponding acid halogenides, for example by the action of thionyl chloride. The p-alkoxy-benzoyl chlorides obtained then are allowed to react with alkylenic chlorhydrine, for example ethylene chlorhydrine or propylene chlorhydrine.

Instead of the p-alkoxy-benzoyl halogenides the free p-alkoxy-benzoic acid or esters of the p-alkoxy-benzoic acid may be used for the reaction with the alkylenic chlorhydrines, but the yields obtainable are not so good as when the p-alkoxy-benzoyl halogenides are used.

The product obtained by the reaction of the p-alkoxy-benzoyl halogenides with the alkylenic chlorhydrines is allowed to react at an elevated temperature and under pressure with a dialkyl amine some other secondary base, as for example piperidine.

The chlorhydrate of the dialkyl amine or of some other secondary base is separated from the water insoluble ester of the p-alkoxy-benzoic acid by treating the mass with water. The ester is extracted with ether and the ethereal layer reextracted with dilute acid, when the chlorhydrate of the basic ester goes into the aqueous layer.

For further purification the ester can be liberated from the solution by alkalization and be

reextracted with ether. The corresponding acid must be added to the ethereal solution in order to precipitate the salt required.

Another way to prepare the new compounds is given by the direct action of p-alkoxy-benzoyl chlorides on suitable dialkyl-amino alcohols.

The new preparations have, as already mentioned, a strong locally anaesthetizing power. This was not to be expected, particularly since the corresponding compounds, which are derived from p-alkoxy-benzoic acids having the phenolic hydroxyl-group substituted by alkyl residues with less than 3 carbon atoms, have very little locally anaesthetizing power. The chlorhydrates of the diethylamino-ethenyl p-n.butoxy-benzoate and p-isoamyoxy-benzoate respectively are more than a hundred times more active than for example the chlorhydrate of the diethylamino-ethenyl p-methoxy-benzoate.

20 The physiological experiments for the estimation of the locally anaesthetizing power of the new preparations were carried out as follows:

Frogs are decerebrated with a sharp needle avoiding hemorrhages, suspended on a gallows 25 and the hind legs dipped into the solution to be tested. The anaesthetizing solution is exchanged in certain intervals for a 2% acetic acid solution and the frog's reaction to this irritation is observed.

30 It was found that diethylamino-ethenyl p-n. butoxy-benzoate and the corresponding ester of the p-isoamyoxy-benzoic acid are still active, when applied in 0.06% solution. Diethylamino-ethenyl p-methoxy benzoate had to be applied 35 in solution stronger than 6% in order to produce an effect of local anaesthesia.

The new local anaesthetically active preparations are in the first place to be used in aqueous solutions, but it is possible, if required, to prepare 40 muconic solutions or to use the preparations as addition to ointments or nose emulsions.

The diethylamino-propenyl p-n.butoxy-benzoate proved to be particularly active as its threshold of activity was smaller than 0.03%.

45 Example I

A mixture of 25 g. p-n.butoxy-benzoic acid and 200 g. thionyl chloride is heated in a Claisen flask on a water bath until the acid has 50 gone into solution, when the product is fractionated in vacuo. The acid chloride distills at 160° at 13 mm. Hg. 12 g. ethylene chlorhydrine are added to the distillate and the mixture is heated on the water bath till no more hydrochloric acid is formed. The product is shaken 55 in a tap funnel with water and a little sodium carbonate solution, the chloroethyl ester extracted with ether, the ethereal solution dried over anhydrous sodium carbonate and evaporated. The residue melts at 32°. Yield 27 g. corresponding to 82% of the theory.

12 g. of the resulting ester are heated for 30 hours in a sealed tube in an atmosphere of nitrogen together with 15 g. diethylamine. The 60 product of the reaction is treated with water, when diethylamine chlorhydrate is dissolved the aminated ester separating as an oil. The oil is extracted with ether, the ethereal solution washed with dilute hydrochloric acid, the acidic extract 65 shaken for an hour with charcoal, filtered, the filtrate made alkaline by the addition of potassium carbonate and the oil re-extracted with ether. The ethereal solution is dried over anhydrous sodium carbonate. By carefully introducing anhydrous HCl-gas under cooling, the 70

chlorhydrate is precipitated in small crystals. The precipitate is separated by filtration, dried on pieces of porous material and recrystallized from absolute alcohol. The chlorhydrate melts at 146°.

5 Example II

p-isoamyoxy-benzoyl chloride is prepared as in Example I from p-isoamyoxy-benzoic acid by means of thionyl chloride and boils at 172° at 12 mm. Hg. The reaction between the acid chloride and ethylene chlorhydrine is carried out as described in Example I and the β -diethylamino-ethenyl p-isoamyoxy benzoate is obtained by heating the β -chloroethyl p-isoamyoxy benzoate for 40 hours with diethylamine at 110°. The 15 products of the reaction are worked up as in Example I. The chlorhydrate melts at 128°.

Example III

90 g. p-n. butoxy-benzoic acid are treated 20 with thionyl chloride. The acid chloride obtained (B. P. 169° at 18 mm. Hg) is treated with trimethylene chlorhydrine (50 g.). γ -diethylamino-propenyl p-n.butoxy-benzoate is prepared by 25 heating the resulting ester (107 g.) for 65 hours at 100° with diethylamine (160 g.). The products of the reaction are worked up as in Example I. The other experimental details correspond closely to those in Example I. The chlorhydrate melts at 126-127°.

Example IV

The acid chloride is prepared from 79 g. p-n.-butoxy-benzoic acid by means of thionyl chloride and boils at 166° at 15 mm. Hg. It is treated 35 with 40 g. ethylene chlorhydrine and the resulting ester is heated for 60 hours at 100° with a solution of 50 g. dimethylamine in 67 g. benzene in order to get the dimethylamino ester. Working up and experimental details as in Example I. The chlorhydrate melts at 127-128°.

Example V

The acid chloride is prepared from 80 g. p-n.-propoxy-benzoic acid by means of thionyl chloride and treated with 40 g. ethylene chlorhydrine. The resulting ester is heated for 50 hours at 100° with dipropylamine (100 g.) to give the di-n.propylamino ester. Working up and experimental details as in Example I. The chlorhydrate melts at 119°.

Example VI

As described in Example III p-n.butoxy-benzoyl chloride is prepared from p-n.butoxy-benzoic acid by means of thionyl chloride. 51.5 g. p-n.-butoxy-benzoyl chloride are diluted with a mixture of benzene-toluene (boiling point 100°), a solution of 28.3 g. diethylamino-ethanol in 155 g. of the same benzene-toluene mixture is slowly added and the mass refluxed for 24 hours. The cool solidified mass is carefully shaken with dilute hydrochloric acid, separated from the benzene-toluene layer, shaken with charcoal and filtered. The base is liberated by the addition 60 of sodium carbonate, extracted with ether and the ethereal solution dried over anhydrous potassium carbonate. By the careful introduction of anhydrous HCl-gas the base is precipitated as chlorhydrate which is recrystallized from a hot benzene-toluene mixture containing a little alcohol and finally melts at 146-147°. Yield approximately 65% of the theory.

What I claim is:

1. A water soluble salt of a dialkylamino al-

kanol ester of a p-alkoxy benzoic acid of the following type:

carbon atoms, R^2 is a propylene residue, R^3 and R^4 are two alkyl residues, and Ac is an acid radical forming a water soluble salt with the ester of the amino alcohol.

7. As a new compound, the chlorhydrate of β -diethylamino-ethenyl p-n.butoxy-benzoate. 5

8. As a new compound, the chlorhydrate of β -diethylamino-ethenyl p-isoamyoxy-benzoate.

9. As a new compound, the chlorhydrate of γ -diethylamino-propenyl p-n.butoxy-benzoate. 10

10. Method for the preparation of water soluble compounds of the following type:

where R^1 is an alkyl residue with 3-6 carbon atoms, R^2 is an alkylene residue, R^3 and R^4 are two alkyl residues, and Ac is an acid radical forming a water soluble salt with the ester of the amino alcohol, comprising the alkylation of p-hydroxy benzoic acid, followed by the conversion of the p-alkoxy benzoic acid into the corresponding benzoyl halogenide by the action of an inorganic acid halogenide, followed by the reaction of the benzoyl halogenide with an alkylene chlorhydrine followed by the heating of the product obtained with an excess of a dialkyl amine under pressure and by conversion of the resulting basic 30 ester into a water soluble salt.

11. Method for the preparation of water soluble compounds of the following type:

where R^1 is an alkyl residue with 3-6 carbon atoms, R^2 is an alkylene residue, R^3 and R^4 are two alkyl residues, and Ac is an acid radical forming a water soluble salt with the ester of the amino alcohol, comprising the alkylation of p-hydroxy benzoic acid, followed by the conversion of the p-alkoxy benzoic acid into the corresponding benzoyl halogenide by the action of an inorganic acid halogenide followed by the reaction of the resulting benzoyl halogenide with a dialkyl amino alcohol to form the dialkylamino p-alkoxy-benzoate and by transformation of this 50 ester into a water soluble salt.

12. Method for the preparation of water soluble compounds of the following type:

where R^1 is a saturated alkyl residue with 3-6 carbon atoms, R^2 is an ethylene residue, R^3 and R^4 are two alkyl residues, and Ac is an acid radical forming a water soluble salt with the ester of the amino alcohol, comprising the alkylation of p-hydroxy benzoic acid, followed by the conversion of the p-alkoxy benzoic acid into the corresponding benzoyl halogenide by the action of an inorganic acid halogenide, then subjecting the benzoyl halogenide to a treatment which will produce a basic ester of the substituted benzoic acid, and thereupon converting such ester into a water 60 soluble salt.

6. A water soluble salt of a dialkylamino alkano ester of a p-alkoxy benzoic acid of the following type: 65

where R^1 is a saturated alkyl residue with 3-6

CARL ROHMANN.
